TUBE

Anthony Roberts Harris, Hanworth, England, assignor to
Dunhill Lighters Limited, London, England

Filed Apr. 4, 1975, Ser. No. 565,265

Claims priority, application Great Britain Oct. 22, 1974

Term of patent 14 years

Int. Cl. D25—01

U.S. Cl. D54—7

FIG. 1.

FIG. 2.

FIG. 1 is a side view of a tube, embodying the design; and

FIG. 2 is an end view of the tube.

The important feature of my design for a tube is the cross-sectional shape which is the same as that shown in the end view seen in FIG. 2.

I claim:

The ornamental design for a tube, as shown and described.
